UNITED STATES PATENT OFFICE

VIRGIL OLDBERG, OF DETROIT, MICHIGAN, ASSIGNOR TO OLDBERG MANUFACTURING COMPANY, OF DETROIT, MICHIGAN, A CORPORATION OF MICHIGAN

MUFFLER

Application filed October 26, 1931. Serial No. 571,136.

This invention relates to mufflers and more particularly to automobile engine mufflers of the thru type.

Mufflers of the thru type, include an outer shell having heads which are connected by and thru which passes an inner shell, the latter being entirely free of baffles, etc., and being provided with perforations, between the heads, leading into the annular space between the shells. Mufflers of this type are advantageous in that they are free from back pressure, and if suitable means between the shells be provided to absorb or neutralize sounds arising within the mufflers, the muffler is found to be highly efficient as a means for eliminating noises which occur in engine operation.

An object of the invention, therefore, is a muffler of the thru type provided with means in the annular space between the shells, to neutralize sounds. More particularly, the invention aims to provide resonators in the space between the shells, as contrasted with mufflers, such as have previously been provided, and which include sound absorbing media disposed between the shells.

A still further object is a muffler of the character above described which is provided with a baffle at its end to prevent flames from passing out of the muffler.

A still further object is a muffler having transverse diaphragms between the shells, the diaphragms being formed of ribs extending inwardly or outwardly from one or more of the shells, as desired.

Still further objects will readily occur to those skilled in the art upon reference to the following description and the accompanying drawings in which:

Fig. 1 is a half longitudinal section of one form of the muffler.

Fig. 1a is a similar section showing a slightly modified form.

Fig. 2 is a longitudinal central section showing a still further modified form.

Figs. 3 and 4 are longitudinal sections showing the type of muffler of Figs. 1 and 2 with the addition of a resonator.

Fig. 4a is a section showing a modification of Fig. 4.

Fig. 5 is a section thru Fig. 3 on the line 5—5.

Figs. 6 and 6a are longitudinal sections thru the muffler involving some of the features of Figs. 2, 4 and 4a.

Figs. 7 to 10 show further modifications.

Referring to the drawings and more particularly to Figs. 1 and 1a, it will be seen that the muffler of this form includes an outer imperforate shell 10 provided with heads 12 and 13 which are connected by an inner shell 14 passing thru both of the heads. In the annular space between the shells are diaphragms 16 and 18 which reinforce the muffler and also form resonating chambers, indicated at R. A plurality of small, closely spaced perforations 19 in the shell 14 afford communication between the interior of the shell 14 and the several resonating chambers.

In Fig. 1a a similar construction is shown except that the diaphragms 16a and 18a will be of conical form to which reference will be made later.

It will be seen that the gases from the engine pass thru the inner shell 14 without obstruction and that sounds within the muffler are resonated by the bodies of gas in the resonating chambers R, the fluid bodies within such chambers being separated by the diaphragms 16 and 18.

In Fig. 2 there is disclosed a muffler including an outer shell 20 having heads 21, and a diaphragm 21a the latter and the after head 21 supporting the tube 14, which is similar in all respects to the tube 14 of Fig. 1. Between the forward head 21 and the diaphragm 21a is a receiving chamber 22 into which the gases pass from the motor, being then led out thru the tube 14 in the fashion indicated in Fig. 1. In this form of muffler, the tube 14 is shown as supported by conical diaphragms 18a as in Fig. 1a. This provides resonating chambers R between the diaphragms 18a as in the previous forms, but a further modification in this figure is shown in providing the diaphragm 21a with openings 22a thru which a part of the gases pass into the chamber 23 and then back into the tube 14 thru the holes 19, passing on out thru the discharge end of the tube.

In Figs. 3 to 5, there is disclosed another form of the muffler. The muffler of this form includes an outer shell 30 provided with end heads 31, each of which is provided with a nipple 32. Within the shell 30 and spaced from the end heads, are auxiliary heads 33, these being connected by the inner tube 34 and the intermediate shell 35. The inner shell 34 is provided with minute perforations 36, opening into the space between the inner parts 34 and 35 which is filled with a sound absorbing media 37, such as steel wool, mineral wool, or loosely packed fiber or the like. The space between the shells 30 and 35 contains two resonating diaphragms 38 which form resonating chambers R, communicating with the spaces between the heads 31 and 33 thru slots 39 in the outermost portions of the heads 33. It will be seen that in this form the gases pass from one nipple 32 to the other without interference, there being no baffles in the path of flow of the gases. Certain of the gases, however, pass from the spaces between the heads 31 and 33, thru the slots 39 and into the resonating chambers R, to set up resonating vibrations in these chambers.

In the form shown in Figs. 4 and 4a, the structure is quite similar to that of Figs. 3, except that instead of the media 37, this is replaced with a plurality of chambers 37a produced by the insertion of the diaphragms 37b in Fig. 4 and 37c in Fig. 4a, the difference in the diaphragm being that the latter are conical rather than plane.

Figs. 6 and 6a show forms of mufflers which correspond most nearly to that of Fig. 4, but with the modification shown in Fig. 2. In this figure, the outer cylinder 20 is, of course, the outer imperforate wall and the inner cylinder is, of course, the tube 14 with the perforations 19. The resonating chamber R opens out of the chamber R' through the openings 22c which are of considerable size. The secondary resonating chambers R² are constructed and operate in the same manner as the corresponding chambers in the previously described forms.

In Fig. 6a there is shown a construction which is similar to that of Fig. 6, except that there is a receiving chamber C for the gases and this chamber communicates with the resonating chamber R through the openings 22d and also communicates with the tube 14 through the chamber 23a through openings 22a and perforations 19, as in Figs. 2.

In Fig. 7 there is shown a muffler which is very much like those disclosed in the previous figures, except that in the space between the slotted head 41 and the end head 42 a conical perforated baffle 43 is disposed, and baffle opening towards the exit nipple 44. A baffle of this character serves the useful purpose of preventing flames which

might be present in the muffler from passing out thru the nipple 44.

In Figs. 8, 9 and 10, there are disclosed mufflers which are very much like the muffler of Fig. 6a, except that the diaphragms in the space between the inner shell 50 and the intermediate shell 51 are formed by rolled annular ribs 52 integral with the inner shell and projecting outwardly therefrom and into engagement with the intermediate shell 51 forming resonating chambers R similar to those disclosed in Fig. 1. Resonating chambers of a trapezoidal cross section have proven to be very efficient, much more so than resonating chambers of the rectangular cross section of Fig. 2.

In Fig. 9 there is disclosed a muffler which is more or less like the muffler of Fig. 8 except that the partitions between the inner shell 60 and the intermediate shell 61 are formed by rolled annular ribs 62 projecting inwardly from the intermediate shell and engaging the wall of the inner shell to form resonating chambers R of trapezoidal cross section.

Fig. 10 discloses a muffler which is also very much like the form of Fig. 8 except that the diaphragm between the inner shell 70 and the intermediate shell 71 comprise annular ribs 72 rolled outwardly from the inner shell and annular ribs 73 rolled inwardly from the intermediate shell. These ribs engage one another and are secured to one another to form transverse partitions to form resonating chambers R which, as disclosed, have a lozenge shaped cross section having all of the advantages of the trapezoidal cross section resonating chambers disclosed in Figs. 7 and 8.

The simplest form of muffler shown in the drawings, is, of course, that shown in Fig. 1 which provides merely the lateral resonating chambers. However, it has been found that if the diaphragms are formed conical in shape a further effect in eliminating noise is gained. It seems to be that the exact angle will vary with different conditions but satisfactory results have been obtained through the use of angles ranging from 20 degrees up to 90 degrees with a maximum efficiency near the central point of this range. The inclination of the diaphragm chamber toward or away from the rear end seems to make little difference.

It has also been found that if a proportion of the gases are shunted from the receiving chamber and introduced into the outlet tube at a short distance away from the chamber, a further effect in decreasing noise will be obtained. These effects can, of course, be obtained without increasing the back pressure of the muffler, which back pressure in the form shown, is practically zero.

Now having described the invention and the preferred embodiment thereof, it is to be

understood that the said invention is to be limited, not to the specific details herein set forth, but only by the scope of the claims which follow:

5. What I claim is:

1. In a muffler for the exhaust gases of an internal combustion engine, wherein exhaust gases and sound waves travel in the same direction, the combination of an intermediate shell having apertured end headers, a shell telescoped therein and providing a thru and unobstructed passage for exhaust gases thru the muffler from an engine to the atmosphere, the latter shell having a relatively large portion of its entire surface covered with a plurality of relatively small, closely spaced, perforations, there being a plurality of annular, spaced, substantially imperforate diaphragms in the annular space between the 10 aforementioned shells to provide a plurality of annular, elongated, sound attenuating chambers in said space, the perforations opening into said chambers, the muffler also having an outer imperforate shell surrounding the aforementioned shells, the outer shell being closed at its ends and also being placed in communication with the interior of the intermediate shell thru large openings therein. 70
2. In a muffler for the exhaust gases of an internal combustion engine, wherein exhaust gases and sound waves travel in the same direction, the combination of an intermediate shell having apertured end headers, a shell telescoped therein and providing a thru and unobstructed passage for exhaust gases thru the muffler from an engine to the atmosphere, the latter shell having a relatively large portion of its entire surface covered with a plurality of relatively small, closely spaced, perforations, there being a plurality of annular, spaced, frusto-conical, substantially imperforate diaphragms in the annular space between the aforementioned shells 15 to provide a plurality of annular, elongated sound attenuating chambers in said space, the perforations opening into said chambers, the muffler also having an outer imperforate shell surrounding the aforementioned shells, the outer shell being closed at its ends and also being placed in communication with the interior of the intermediate shell thru large openings therein. 75
3. In a muffler for the exhaust gases of an internal combustion engine, wherein exhaust gases and sound waves travel in the same direction, the combination of an intermediate shell having apertured end headers, a shell telescoped therein and providing a thru and unobstructed passage for exhaust gases thru the muffler from an engine to the atmosphere, the latter shell having a relatively large portion of its entire surface covered with a plurality of relatively small, closely spaced, perforations, there being, in the an- 80
- nular space between the aforementioned shells, means for attenuating, to a marked degree, sound waves caused by gases coursing thru the innermost shell, the perforations opening into said annular space, the muffler also having an outer imperforate shell surrounding the aforementioned shells, the outer shell being closed at its ends and also being placed in communication with the interior of the intermediate shell thru large openings 85
- therein. 90
- 95
- 100
- 105
- 110
- 115
- 120
- 125
- 130

In testimony whereof, I sign this specification.

VIRGIL OLDBERG.
